Primary Examiner — Stacia Cadmus*(74) Attorney, Agent, or Firm* — Frommer Lawrence & Haug LLP; Marilyn Matthes Brogan; Paul A. Levy(57) **CLAIM**

The ornamental design for a wheel rim, as shown and described.

DESCRIPTION

FIG. 1 is a front perspective view of a wheel rim according to my invention

FIG. 2 is a rear perspective view thereof;

FIG. 3 is a side perspective view thereof;

FIG. 4 is a front view thereof; and,

FIG. 5 is a rear view thereof.

The broken lines shown in the figures are for the purpose of illustrating structure that forms no part of the claimed design.
